UNITED STATES PATENT OFFICE

MARTIN A. MORRISSEY, OF ROSLINDALE, AND ALMER F. MOORE, OF BRIGHTON,
MASSACHUSETTS

METHOD OF PREPARING CONCRETE

No Drawing.

Application filed October 1, 1930. Serial No. 485,658.

Our invention relates to the art of making concrete and has for its object the provision of an improved method or process of preparing the same to insure its proper strength after hardening or setting. The invention consists in regulating the amount or proportion of moisture in a given quantity of mixture by the removal of substantially all excess free moisture from the mass after the mixing operation has been performed and while the mass is still in a fluid state, that is to say, by the removal promptly after the cement or other auto-solidifying substance has been subjected to the moisture and permitted to become thoroughly hydrated, of all moisture in and throughout the mixture in excess of requirements for moistening the inert matter and for fully hydrating the cement.

With a view to a clearer understanding of the present mode of treatment and its effect, some preliminary observations as to the usual practices in making concrete are desirable. The quantities of the various solid ingredients, including cement and inert matter, employed in preparing a mixture for a definite work or structure are usually fixed upon in advance of the undertaking, each being assigned a definite relative proportion or value in terms usually of bulk or weight, this estimate being based upon common experience. Comparatively slight consideration is given in any given undertaking to the correct relative proportion of water employed for effecting the necessary chemical change in the cement to give it the proper strength. Too much or too little water are both detrimental to the desired result, it being always self-evident that insufficient moisture would fail in effecting the chemical change in the powdered cement necessary to give it adhesive strength and solidifying properties, while it is now increasingly appreciated by those engaged with the commercial use of concrete that any large excess of water is also destructive in its effect.

As a corrective measure the quantity of water supplied the mixing chamber is only roughly estimated with respect to the volume of the solid ingredients employed, irrespective of their character and condition. The results, while partially cor-

rective in many instances, are not uniformly so and far from approximating scientific accuracy and dependability. This is attributed to the fact that moisture is always present to a varying extent in or on the inert matter as used in commercial practice, and it cannot practicably be determined in advance of the actual mixing operation what is the proper quantity of water to be used in each individual mixture.

From laboratory tests of samples of different batches taken from the same construction job, alike in so far as the relative proportions of solid matter are involved but differing in the content of water, it has been shown that the compressive strength of the mass after like periods of setting show a variance sometimes amounting to 50%, the resultant product in some instances being below that required for safety and durability.

While commercial practices do not favor the attainment of absolute accuracy in apportioning materials in making concrete, a reasonable range of variation, while relatively small in correct practice, is permissible in the proportion of water to the remaining ingredients for different batches on the same job. Keeping within the allowable range of variation, we have discovered, can best be attained by removing the excess free moisture from each batch separately after the mixing operation has been substantially completed and while the mass is still in a fluid state, preliminary to setting or hardening. The removal of this excess moisture may be accomplished with practical success in various ways such as, for example, by centrifuging, absorption, filtration, etc., or a combination thereof.

In practicing our method or process of making concrete, an intimate mixture of cement, such as Portland cement or other auto-solidifying substance, with an aggregate comprising one or more inert substances such as sand and/or gravel, in the presence of water, supplied in accordance with any usual or approved formula, such, for example, as two parts by volume of sand and four parts of gravel to one part of cement, with sufficient water to readily form a co-

hesive fluid mass, is first made up in the usual manner. The mixing operation may be performed either by hand or with machinery, including any suitable mixing devices.

5 And while it is indispensable to the production of a good quality of concrete that approved practices regarding the use of ingredients of approved character, in proper proportion and properly mixed be observed, 10 our improvements in the art are more directly concerned with the condition and treatment of concrete in the mixed mass while in a fluid state, than with the mixing operation itself.

15 It is not essential to the utility of our method that the quantity of water employed in the mixture during the mixing operation be accurately measured before introduction to the mixing chamber. It may even largely 20 exceed the amount necessary to properly hydrate the cement. Nor is it necessary that the inert ingredients be heated or otherwise dried out before introduction to the mixing chamber. It is, however, important that the

25 mixing operation be substantially fully performed before commencement of the operation of removing the excess water, in order to insure the thorough conversion of the cement from an inert to an active state, and that 30 after such conversion the excess water in and throughout the mixture be removed before the cement sets. By the term "excess water" we refer to that portion of the total volume of water or moisture present in the mixed 35 mass which, if not removed at or before the commencement of setting or hardening of the mass, impairs the strength and quality of the concrete after setting, such "excess" being substantially that portion of the water not 40 required to properly hydrate the cement and to moisten the inert matter preliminary to hardening or placing of the concrete.

In carrying out our invention we provide a 45 suitable receptacle, which may be of any convenient size or shape, to receive the concrete after the mixing operation has been fully or substantially performed. It is not essential to the successful application of our invention that the original mixing chamber or apparatus be used for this purpose, although it 50 may conveniently serve, nor that the entire mass be uniform in density or in water content with respect to itself or other batches. We prefer, in fact, to employ a separate receptacle of suitable proportions and conveniently arranged to readily accommodate periodic discharges from the mixing apparatus or other source of supply. Within this ultimate receptacle are placed or provided suitable water removing means, as, for example, a pipe or conduit (not shown) having an inlet and provided with a filtering nozzle extending into the body of the mixture and an outlet end extending beyond the mixture and 55 connected to suitable mechanism for pro-

ducing suction of a predetermined strength adequate to remove the excess moisture within and throughout the mixture but none of the moisture required to fully hydrate the cement and moisten the inert substances. 70 Said filtering nozzle should be designed to effectively reach and drain substantially all parts of the interior, including the entire mass of concrete contents, of excess moisture. 75

Although a substantial portion of the excess water may rise to the surface of the mass if the latter be permitted to stand undisturbed a sufficient length of time, whether this result be accomplished by gravity alone 80 or in conjunction with tamping or other artificial means, this gravitational or settling method is found to be unnecessarily timetaking, deficient in thoroughness and otherwise objectionable. By our present method or means the entire mass mixture is penetrated and drained simultaneously and thoroughly 85 before commencement of the hardening or setting of the concrete.

In the application of our improved method or process of preparing concrete it is important that the dewatering operation, by whatever means effective for the ends described this be accomplished, should be commenced, adequately performed and fully completed within certain limitations in point of time namely, immediately or shortly after the exposed or accessible surfaces of all particles of inert materials have become moistened and the entire body of cement or other auto-solidifying substance has been completely hydrated, and before the latter has appreciably begun to set or harden. It is equally important that the dewatering operation be extended to all parts of the mixture, 100 as well within and throughout the same as the exposed surfaces. It should be further pointed out that whatever means are employed for removal of the excess moisture, 105 it is important also that the coercive force applied should be so regulated or controlled that only the excess moisture, and none of the moisture necessary to moisten the inert matter and fully hydrate the cement, be removed.

110 It will be understood that our invention is not restricted to the precise details of the operations herein described but embraces obvious modifications thereof, and is commensurate with the scope of the appended claims.

We claim as our invention:

1. The method of preparing concrete, consisting of intimately mixing an auto-solidifying substance with an aggregate, in the presence of water, then allowing the auto-solidifying substance to become hydrated, 125 and thereupon applying dewatering means to exert a coercive force tending to extract excess water from the mixture said force being regulated and applied to and throughout the body of the mixture. 130

2. The method of preparing concrete, consisting of intimately mixing an auto-solidifying substance with an aggregate, in the presence of water then allowing the auto-solidifying substance to become fully hydrated, and then applying suctional dewatering means to all parts of the mixture to remove the excess water before the mixture has begun to harden. 75
- 10 3. The method or process of preparing concrete, consisting of intimately mixing an auto-solidifying substance with an aggregate consisting of one or more inert substances, in the presence of water, then allowing the auto-solidifying substance to become fully hydrated, and thereupon removing the excess water by dewatering means adapted to exert a predetermined extractive force applied throughout the mixture. 80
- 15 4. The method or process of preparing concrete, consisting of intimately mixing an auto-solidifying substance with an aggregate, consisting of one or more inert substances, in the presence of water, then allowing the auto-solidifying substance to become fully hydrated, and thereupon filtering and removing excess moisture from the mixed mass by suctional means. 85
- 20 5. The method or process of preparing concrete, consisting of intimately mixing an auto-solidifying substance with an aggregate consisting of one or more inert substances, in the presence of water, then allowing the mixture to remain undisturbed for a limited period of time, and thereupon removing the excess water from the mixed mass by means of filtration involving suction. 90
- 25 6. The method or process of preparing concrete, consisting of intimately mixing an auto-solidifying substance with an aggregate, in the presence of water, then allowing the auto-solidifying substance to become fully hydrated, and then dewatering the mixture by removing the excess moisture by filtration induced by suction having a predetermined coercive force. 95
- 30 7. The method or process of preparing concrete, consisting of intimately mixing an auto-solidifying substance with an aggregate, in the presence of water, then allowing the auto-solidifying substance to become fully hydrated, and then applying controlled dewatering means to exert a regulated extractive force to and throughout the mixture to remove only the excess water. 100
- 35 8. The method or process of preparing concrete, consisting of intimately mixing an auto-solidifying substance with an aggregate, in the presence of water, then allowing the auto-solidifying substance to become fully hydrated, and then dewatering the mixture by filtration induced by suction having only sufficient coercive force to remove all the moisture in excess of requirements for moistening the aggregate material and for 105
